UNITED STATES PATENT OFFICE

SIDNEY D. WELLS, OF QUINCY, ILLINOIS, ASSIGNOR, BY MESNE ASSIGNMENTS, TO THE MINE & SMELTER SUPPLY COMPANY, OF DENVER, COLORADO, A CORPORATION OF COLORADO

PROCESS FOR PRODUCING FIBROUS MATERIAL

Application filed September 27, 1927. Serial No. 222,353.

My invention relates to improvements in processes for producing fibrous material and more specifically to the production of straw pulp, although applicable to the production of other varieties of pulp.

In the production of straw and other varieties of pulp, the material is first treated to a mild digestion with suitable chemicals, as is well known in the art, to the point where the bond between the fibers and the cells is reduced, but not completely removed. After this treatment, the material is mechanically disintegrated and beaten to produce the finished pulp.

If the material is beaten in the presence of the spent cooking or digesting liquors, the fibers are injured by the products of decomposition from the cooking operation being beaten into the stock with the attendant loss of cellular matter, and lower quality of the product.

An important object of my invention is to obviate these difficulties by a treatment of the stock in which the stock is washed free from the spent cooking liquor before being beaten.

Other objects and advantages of my invention will be apparent during the course of the following description.

In the accompanying drawing which forms a part of this specification and wherein like characters of reference denote like parts throughout the same,

The figure is a more or less schematic representation of the apparatus used by my process, illustrating the sequence of the various steps thereof.

In carrying out my process, the stock, which has been treated to a mild digestion with suitable chemicals to the point where the bond between the fibers and the cells is reduced but not completely removed, is taken from the rotary or storage, and passed through a shredder or pulverizer illustrated diagrammatically at 1, together with wash water taken from a subsequent point in the process through pipe 2. The shredder is preferably, but not necessarily, of the swing hammer type, and the stock is shredded therein without washing and put into a

condition such that it can be readily pumped. This mechanical disintegration is carried to the point where the water present in the shredder may gain ready access to the fibrous constituents of the stock, but not to the point where the fibers are completely isolated.

The shredded material drops into stuff chest 3 where it is kept thoroughly mixed by the agitator 4 arranged within the chest.

From the stuff chest 3 the stock, which is mixed with wash water and in condition to be readily pumped, is pumped by pump 5 to a gate box 6 of the usual construction

where it is maintained at a constant level by the pump 5 and overflow pipe 7 leading back to the stuff chest 3. The proper quantity of stock passes through the gate 8 into the mixing compartment 9 of the cylinder washing machine designated generally at 10 where it is mixed with liquid from a subsequent point in the process supplied through pipe 11.

The mixture passes on to cylinder mold 12 where a sheet is formed and taken off by couch roll 13 from whence it is scraped into the mixing box 14, the spent cooking liquor washed from the cooked stock passing from cylinder mold 12 through pipe 15 to the sewer.

The sheets scraped from couch roll 13 are mixed with fresh water from the pipe 16, in the mixing box 14 by means of the agitator 17, and the thoroughly mixed water and pulp pass on to cylinder mold 18 where the pulp is again formed into a sheet, picked up by couch roll 19 and scraped into trough 20, the water passing from cylinder mold 18 through pipe 21 to pipe 11 which supplies pipe 2 and mixing chamber 9 with the wash water, by means of centrifugal pump 21'.

Trough 20 conveys the thoroughly washed stock to the rod mill 22 where it is rolled and beaten by the freely tumbling rods therein as is fully set forth in my application No. 49,461, filed August 10, 1925 which matured into Patent No. 1,654,624 of January 3, 1928. While I have illustrated a rod mill, and prefer to use the same, it is to be understood that I do not limit myself to

this type of beater but contemplate the use of other types of beaters or refining engines, as for instance, a Jordan engine.

The stock is beaten in the rod mill 22, or 5 other beating or refining engine, to the desired degree and passes into stuff chest 23 where it is maintained in uniform consistency by the agitator 24, in condition to be pumped to the paper machines by pump 25.

10 In the process as outlined above the stock is first shredded without washing, preferably in a swing hammer shredder, where it is put into a condition whereby it can be pumped without difficulty. It can then be 15 pumped over a cylinder mold type of washer which is much more efficient for the purpose than the drum washers now used on beaters. When the stock has been thoroughly washed, it can be beaten to the desired degree without 20 the injury to the fibers or quality of the product like that which takes place when the stock is beaten in the presence of the spent cooking liquor. In the process as formerly practiced, however, the cooked 25 straw is taken into beaters provided with drum washers, and washed while it is beaten. This method of beating and washing at the same operation is not only detrimental to the straw stock, but requires much 30 greater quantities of water than the system which I have outlined. It is also true that even with the larger quantities of water used in the old process, the straw paper contains from 30 to 40 per cent of the lime originally 35 used in the cook.

In my process the steps of shredding, washing and beating are carried out separately and independently, with the use of a 40 small amount of water as compared with the old processes, and a higher quality of product is obtained.

Having thus described my invention what I claim and desire to protect by Letters Patent is:

45 1. The process of producing fibrous material which consists in treating the material to a mild chemical digestion to the point where the bond between the fibers and cells is reduced but not completely removed, subjecting the softened material to a preliminary 50 mechanical disintegration in the presence of water, washing the material, and subjecting the washed material to a final mechanical disintegration.

55 2. The process of producing fibrous material which consists in treating the material to a mild chemical digestion, shredding the softened material in the presence of water, pumping the shredded material to a washing device, thoroughly washing the shredded material to free it from the spent cooking liquor, conveying it to a beating device and beating it to the desired degree.

60 3. The process of producing fibrous material which consists in treating the material

to a mild chemical digestion to the point where the bond between the fibers and the cells is reduced but not completely removed, subjecting the softened material to mechanical disintegration in the presence of water 70 to the point where the water may gain ready access to its fibrous constituents and the fibers are not completely isolated, washing the disintegrated material with water in the absence of any heating action to free the material from the spent cooking liquor, and completing the mechanical disintegration of the previously washed material. 75

4. The process of producing fibrous material which consists in shredding the material in the presence of water, agitating the shredded material to thoroughly mix it with the water, washing the shredded material, and subjecting the washed material to the action 80 of freely tumbling elements in a rotating drum. 85

5. The process of producing fibrous material, which consists in treating the material to a mild chemical digestion, shredding the softened material in the presence 90 of water, mixing the material with the water, washing the spent cooking liquor from the material, and subjecting the washed material to the action of freely tumbling elements in a rotating drum. 95

6. The process of producing fibrous material which consists in treating the material to a mild chemical digestion, shredding the softened material in the presence 100 of water, agitating the shredded material and water, washing the material to free it from the spent cooking liquor, subjecting the washed material to the action of freely tumbling elements in a rotating drum, and agitating the material to maintain it at 105 uniform consistency.

7. The process of producing straw pulp which consists in treating the straw to a 110 mild chemical digestion, shredding the softened straw in the presence of water, agitating the straw and water, washing the straw, mixing with fresh water and rewashing, and subjecting the thoroughly washed straw to the action of freely tumbling elements in a rotary drum.

8. The process of producing straw pulp which consists in treating the straw to a mild chemical digestion, shredding the straw in the presence of water taken from a subsequent point in the process, agitating the shredded straw and water, mixing the straw with water from a subsequent point in the process, washing the spent cooking liquors from said straw, draining the spent cooking liquor, mixing the straw with fresh water, washing the straw in the fresh water and subjecting the washed straw to the action of freely tumbling elements in a rotating drum. 120

125 9. The process of producing straw pulp 130

which consists in treating the straw to a mild chemical digestion, shredding the straw in the presence of water taken from a subsequent point in the process, washing the straw in a counter current washing device and subjecting the washed straw to a beating and refining treatment.

10. The process of producing fibrous material which consists in treating the fibrous material to a mild chemical digestion, shredding the material in the presence of water, washing the material in a counter current washing device to free it from the spent cooking liquors, and subjecting the washed material to a beating and refining treatment.

11. The process of producing fibrous material which consists in treating the material to a mild chemical digestion, shredding the softened material in the presence of water, mixing the material with the water and conveying it to a washing device, washing the spent cooking liquor from the material, and subjecting the washed material to the action of beating elements.

12. The process of producing fibrous material which consists in partially disintegrating the material to the point at which the interstices in the material do not obstruct the passage of water insoluble impurities, washing the partially disintegrated material to remove impurities, and then mechanically disintegrating the washed material to the point where the fibers are completely separated from each other.

13. The process of producing fibrous material which consists in subjecting the material to a mild chemical digestion, partially disintegrating the material in the presence of the cooking liquors to the point where the interstices in the material do not obstruct the passage of water insoluble impurities, washing the partially disintegrated material to remove impurities, and then mechanically disintegrating the washed material to the point where the fibers are completely separated from each other.

14. The process of producing fibrous material which consists in subjecting the material to a mild chemical digestion, partially disintegrating the material in the presence of the cooking liquors to the point where the interstices in the material do not obstruct the passage of water insoluble impurities, washing the partially disintegrated material to remove impurities therefrom, and then subjecting the washed material to the action of freely tumbling elements in a rotating drum to completely separate the fibers from each other in the absence of cooking liquors and other impurities.

In testimony whereof I affix my signature.
SIDNEY D. WELLS.
